WASTE RECEPTACLE OR THE LIKE

Peter E. Norquest, 2001 Hervey,
Boise, Idaho 83705

Filed Feb. 25, 1970, Ser. No. 21,608

Term of patent 14 years

Int. Cl. D7—99

U.S. Cl. D49—35

FIG. 2

FIG. 1 is a top; front perspective view of a waste receptacle or the like showing my new design in an open position; and

FIG. 2 is a bottom, rear perspective view thereof showing the side opposite that seen in FIG. 1.

I claim:

The ornamental design for a waste receptacle or the like, substantially as shown.
